M. E. CROW,
VEHICLE FRAME BRACE,
APPLICATION FILED AUG. 15, 1919.

1,342,623.

Patented June 8, 1920.

Inventor
Martin E. Crow

By

Louis C. Vanderlip
Attorney.

UNITED STATES PATENT OFFICE.

MARTIN E. CROW, OF ELKHART, INDIANA.

VEHICLE-FRAME BRACE.

1,342,623.

Specification of Letters Patent.

Patented June 8, 1920.

Application filed August 15, 1919. Serial No. 317,684.

To all whom it may concern:

Be it known that I, MARTIN E. CROW, a citizen of the United States, and a resident of the city of Elkhart, county of Elkhart, 5 Indiana, have invented certain new and useful Improvements in Vehicle-Frame Braces, of which the following is a specification.

This invention relates to vehicle frames, and more especially to transverse bracing 10 for automobile frames.

As constructed at present automobile frames have no transverse brace connecting the extreme front ends of the longitudinal side frame members, the nearest transverse 15 frame member being located remotely from the spring connection with the front end of each frame side member. This structure is subject to severe torsional and lateral stresses on rough or uneven roads and is a material 20 weakening factor in the frame of an automobile.

An object of my invention is to provide a transverse brace member connecting the spring carrier members which are mounted 25 upon the extreme forward end of each longitudinal frame side member. Other objects of my invention are mentioned and described herein.

The preferred embodiment of my invention 30 is illustrated in the accompanying drawing in which Figure 1 is a top plan view of a fragment of a motor car frame to which my invention is applied; Fig. 2 is a side elevation thereof showing a fragment 35 of a leaf spring connected therewith; Fig. 3 is a side elevation of the front end of one frame side member and the spring carrier member mounted thereon; Fig. 4 is a section taken on the line 4-4 of Fig. 3; Fig. 5 is a top plan view of one of the spring carrier members showing the brace connection therewith; and Fig. 6 is a section taken on the 40 line 6-6 of Fig. 5. Similar numerals of reference indicate like members throughout 45 the several views on the drawing.

Referring to the drawing in detail, the numerals 1 and 2 indicate the two longitudinal side frame members of a motor car frame which are preferably of channeled 50 metal and which are connected by one or more transverse frame braces 3, one only being shown, as is well known in the art. The frame members 1 and 2 may be parallel or disposed somewhat converging, the latter 55 being the present preferred practice in some vehicle frames. The numerals 4, 4 indi-

cate a pair of front spring carrier members mounted upon the front end of the frame side members 1 and 2, each of said spring carriers having a shank section 5 which is 60 provided with one or more fastener member apertures 6, 6 adapted to be engaged by rivets or bolts, not shown, for securing the same rigidly to the forward end of the side frame members. Preferably, the shank section 65 5 of the carrier 4 is of channel formation and is arranged within the channel portion of the side frame members 1 and 2, and may be tapered and curved to conform with the longitudinal contour of said frame members. 70

Each carrier member 4 may be provided also with a thickened or reinforcing section 7 extending transversely thereof and provided with a fastener member aperture 8 75 which extends entirely through it and longitudinally thereof, said aperture being adapted to be engaged by a rivet 9, or other suitable substitute, the heads whereof engage the outer surfaces of the flanges of the 80 frame members 1 and 2. Numerals 10, 10 indicate oppositely disposed transverse shoulders formed on the upper and lower outer surfaces of the member 4 and against which the flange ends of the side frame 85 members 1 and 2 are adapted to engage to effect greater rigidity between member 4 and said frame member.

The numeral 11 indicates the fragment of a leaf spring the forward end whereof is 90 adapted to project into the opening 12 formed in the member 4, the eye of said spring being engaged by a spring carrier bolt 13 arranged transversely of the opening 12, the outer end of said bolt being mounted 95 in the aperture 14 formed in the outer wall 15 of the member 4, and the inner end of said bolt being screw threaded into the aperture 16 formed in the annular boss 17. The boss 17 may be formed integral with each 100 member 4 and projects laterally therefrom in a horizontal plane, the two bosses being disposed substantially opposite each other and in opposed relation.

The numeral 18 indicates a tubular brace 105 or reinforcing member the opposite open ends whereof are mounted upon the bosses 17 and in encompassment thereof. The end of the tubular brace 18 may engage the annular shoulder 19 of the member 4. Preferably, the brace 18 is welded to each of the bosses 17 to effect the maximum of rigidity 110

and permanency of frame structure, but may be fastened otherwise with good results.

I claim:

1. In a vehicle, the combination of a main frame having spaced longitudinal side members; a spring carrier mounted upon the forward end of each frame side member; a transverse member connecting said carrier members; and a complementary projection and socket connection between each end of said transverse member and one of said spring carriers.

2. In combination with the frame of a vehicle having spaced longitudinal side members, a spring carrier member rigidly mounted upon the end of each frame side member, each of said carrier members being provided with a laterally projecting boss member, said bosses being opposed; and a transverse member having tubular ends, each of said bosses being sleeved by one end of said transverse member.

3. In a vehicle, the combination of a main frame having spaced longitudinal side members; a spring carrier member rigidly mounted upon the forward end of each frame side member and provided with a lateral projection, said projections being opposed substantially; and a tubular transverse brace member, the ends whereof sleeve said spring, 30 carrier projections.

4. In a vehicle, the combination of a main frame having spaced longitudinal side members; a spring carrier member rigidly mounted upon the forward end of each frame side member and provided with a lateral projection, said projections being substantially opposed; and a tubular transverse brace member, the ends whereof sleeve said spring carrier projections and are welded thereto.

In testimony whereof I have hereunto affixed my signature this 8th day of August, 1919.

MARTIN E. CROW.
